UNITED STATES PATENT OFFICE

170,970

BELT

Vladimir A. D'Arbeloff, Riverside, Conn.

Application March 19, 1953, Serial No. 24,123

Term of patent 7 years

(Cl. D3—10)

To all whom it may concern:

Be it known that I, Vladimir A. D'Arbeloff, a citizen of the United States, residing in Riverside, in the county of Fairfield and the State of Connecticut, have invented a new, original, and ornamental Design for a Belt, of which the following is a specification, reference being had to the accompanying drawing, forming a part hereof.

I claim:

The ornamental design for a belt, substantially as shown.

VLADIMIR A. D'ARBELOFF.
